UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

CONDUCTOR HOLDER.

Application filed January 27, 1923. Serial No. 615,266.

To all whom it may concern:

Be it known that I, HOMER P. CHANDLER, a citizen of the United States of America, residing at Mansfield, in the county of Rich-
5 land and State of Ohio, have invented cer-
tain new and useful Improvements in Con-
ductor Holders, of which the following is
a specification.

My invention relates to supports for con-
10 ductors and particularly to that class of
support for gripping a trolley wire and
suspending it from an overhead hanger.

One object of my invention is to produce
a device having incorporated therein means
15 for securing the device to a hanger or other
support, and having means which can be
rotated into alignment with the conductor
and caused to grip the conductor and in
which the parts of which the device is com-
20 posed are held together against disassembly
after being brought into proper assembled
relation.

My invention resides in the new and novel
construction, combination and arrangement
25 of the various parts herein more fully set
forth and described in this specification and
shown in the accompanying drawings. Further
objects of my invention will be
hereinafter disclosed in connection with the
30 detailed description of my preferred form
of construction.

In the accompanying drawing:

Fig. 1 is an end view in elevation of a
35 construction embodying my invention and
showing the same in engagement with the
trolley wire.

Fig. 2 is a side view in elevation of Fig. 1.

Fig. 3 is a transverse section of Fig. 2
40 on the line 3—3.

Fig. 4 is a sectional view of Fig. 3 on
the line 4—4.

Fig. 5 is a transverse sectional view cor-
responding to the view shown in Fig. 3, ex-
cepting that the jaws are shown opened up
45 in condition to receive a trolley conductor.

In the preferred form of construction em-
bodying my invention I employ a support-
ing member 1 having a threaded recess 2
to receive a threaded stud of an overhead
50 support to which the device is secured. The
member 1 is provided with a flange 3 which
screws against the face of the hanger or
support. Intermediate the ends of the mem-
ber 1 is a threaded portion 4 and projecting
55 below the threaded portion 4 is a neck 5,

to the lower end of which is a projecting
flange 6 all forming an annular groove
about the neck 5 between the members 4
and 6. Projecting downwardly on dia-
metrally opposite sides of the member 1
are lugs 7—7 each forming a channel with
the adjacent face of the neck portion 5.
Loosely mounted upon the support member
1 and directly upon the flange 6 are two
clamping members 8—8 independently mov-
able with respect to each other and with
respect to the supporting member 1 and
also rotatable upon the support member 1
about its vertical axis, but limited as to
the extent of rotation. Each jaw member
is provided with a sliding fulcrum edge 9
which engages with the flange 6 and each
clamping member is also provided with an
upstanding collar 10 which fits in the chan-
nel formed by the parts 5 and 7. The ex-
treme ends of the collar 10 are provided
with projections 11 which engage with the
lug 7 and limit the rotation of the mem-
bers 8 relative to the member 1. Each
member 8 is provided with a lip 12 adapted
70 to engage with the trolley conductor 13
and each member 8 is also provided with a
flange 14 and shown as provided with a
beveled face 15.

It will be observed from a study of Figs. 85
3 and 5 that the engagement of the edge 9
with the upper surface of the member 6
forms a sliding fulcrum while the construc-
tion formed by the positioning of the collar
10 in the channel formed by the lug 7 and 90
member 5 produces a true fulcrum about
which the members 8—8 pivot with respect
to the support member 1.

I have found that since the lugs 7—7
engage and hold the clamping members 8—8
from moving outward at the upper end that
I am able to eliminate a twisting or cant-
ing effect upon the members 8—8 when the
member 16 is brought into a rotatable en-
gagement therewith and hence permitting 100
a more positive action of the members 8—8
in gripping the conductor. The same is
true when the member 16 is rotated in the
reverse direction to release the conductor
from the grip of the members 8—8. 105

Mounted on the threaded portion 4 of the
member 1 is an operating member 16 pro-
vided with a threaded recess engaging with
the threads on the portion 4 of the member
1 so that when the member 16 is rotated it 110

will move toward or away from the clamping members 8, depending upon the direction of rotation. Projecting from the lower edge of the member 16 is a circular flange 17 having an inner beveled face arranged to engage with the beveled face 15 of the members 8-8. The opposite edge of the member 16 is provided with a flange 19 which was originally formed straight, as shown by the dotted lines, and which after assembly of the parts is rolled or bent inwardly so as to engage the flange 3 and thereby limit the movement in one direction of the member 16 relative to the members 1 and 8.

15 The member 16 is first positioned upon the member 1 without turning in the flange 19 and the member 16 is positioned near the upper end of the member 1 so that the surface 20 will engage with the flange 3. The members 1 and 8 are then assembled by interlocking the flange 10 within the channel formed between the parts 5 and 7 as indicated in Fig. 5, but there will be no interference of the members 8 with the member 16 because the surface 20 will be in engagement with the flange 3. The relation of the parts 6, 7, 5 and 10 are such as to permit the interlocking of the parts as described. After the parts 1 and 8-8 have been interlocked the member 16 is brought down into engagement with the members 8-8 and the flange 19 turned or rolled inward so as to engage with the flange 3 thereby limiting the movement of the operating member 16 away from the clamping members 8-8 and preventing the flange 17 from moving away from the flange 14 a distance which will permit the members 8-8 to become disengaged from the member 1, that is, the engagement between the members 8-8 and the member 16 is maintained at such a point that the members 8-8 cannot be disengaged from the member 1 after the flange 19 has been formed or rolled inward so as 45 to engage the flange 3.

In order to install the device just described it is only necessary to rotate the device into engagement with the stud of an overhead support or hanger which may be done by grasping the jaws and rotating them in the proper direction which in turn will cause the member 1 to be rotated as the lugs 11 will engage with the lugs 7, or rotation may be brought about by rotating the member 16 in the proper direction which will cause the member 1 to rotate on account of the engagement of the flange 19 with the flange 3. After the device has been secured to the hanger stud it may be found that the 50 clamping members 8-8 are not in alinement with the trolley conductor, but the proper alinement can be brought about by rotating the members 8-8 in the opposite direction from that employed in rotating the member 1, until the jaws are in proper alinement

with the trolley conductor and this back rotation will not rotate the member 1 in a backward direction or loosen it from the hanger stud to which it has been secured on account of the amount of independent rotation permitted the jaws due to the spacing of the lugs 11 on the members 8-8 with respect to the lugs 7 on the member 1.

Having brought the clamping members into alinement with the trolley conductor the jaws are spread apart as shown in Fig. 5 and the trolley conductor inserted between the lips 12-12 and the clamping members 8-8 are then moved into engagement with the trolley conductor by rotating the member 16 in the proper direction to move the lips toward each other. This operation can as a rule be carried out by the hand of the operator, but after the lips are in engagement with the conductor then it is customary to apply a wrench to the faces 21 of the member 16 whereby the member 16 will force the members 8-8 into strong and secure engagement with the trolley conductor.

It will be evident to those skilled in the art that variations may be produced from that just described without departing from my invention. One variation might be the forcing inward of the lugs 7-7 toward the flange 10-10 after the members 8-8 have been interlocked with the member 1 thereby depending on the lugs 7-7 and the flange 10 and the parts 6, 9 and 5 to hold the members 8-8 and the member 1 in position and without the assistance of the member 16 at all.

Having described my invention, I claim:

1. A conductor holder comprising a supporting member having means to secure the member to a hanger, a pair of jaws rotatively mounted on the member and movable towards each other to grip a conductor, means on the jaws to engage means on the supporting member to limit the amount of relative rotation, and means on the supporting member to engage the jaws and move them into engagement with the conductor.

2. A conductor holder comprising a supporting member provided with means to secure the holder to a hanger, a pair of jaws rotatively mounted on the member and movable towards each other to grip a conductor, means on the member to engage means on the jaws to limit the relative rotation of the jaws and member and hold the jaws in place on the member and means on the member to engage the jaws and move them into engagement with the conductor.

3. A conductor holder comprising a supporting member provided with means to secure the holder to a hanger, means to grip a conductor and rotatively mounted on the member, means to limit the relative rotation of the member and gripping means and

means on the member to engage the gripping means and move it into engagement with the conductor.

4. A conductor holder comprising a supporting member provided with means to secure the holder to a hanger, means to grip a conductor and rotatively mounted on the member, means to limit the relative rotation of the member and gripping means and means rotatably mounted on the member to engage the gripping means and move it into engagement with the conductor.

5. A conductor holder comprising means to grip a conductor, supporting means having a relative movement relative to the gripping means, means to secure the supporting means to a hanger, and means to rotate the supporting means into engagement with a hanger when the gripping means is rotated and permitting reverse rotation of the gripping means without rotating the supporting means and means rotatably mounted on the supporting means to engage and move the gripping means into engagement with the conductor.

6. A conductor holder comprising means to grip a conductor, supporting means having a limited rotative movement relative to the gripping means, means to secure the supporting means to a hanger, means to rotate the supporting means into engagement with a hanger when the gripping means is rotated and permitting reverse rotation of the gripping means without rotating the supporting means and means mounted on the supporting means and movable axially thereof to engage the gripping means and move it into engagement with the conductor.

7. A conductor holder comprising a supporting member, means to secure the member to a hanger, clamping means to engage and support a conductor and having a fulcrum engagement with the supporting member, an operating member movable relative to the supporting member and clamping means when rotated relative to the supporting member and the clamping means to move the operating member into and out of engagement with the clamping means to operate the clamping means, means on the clamping means to engage means on the supporting means to prevent the disengagement of the clamping means, and means interposed between the operating member and supporting member after assembly of the parts to maintain the parts against separation.

8. A conductor holder comprising a supporting member and means to secure the member to a hanger, clamping means to grip a conductor and having a limited relative rotation in either direction with respect to the member and arranged to move towards and away from the conductor and

means on the supporting member to limit the movement of the gripping means away from the conductor.

9. A conductor holder comprising a supporting member and means to secure the member to a hanger, clamping means to grip a conductor and having a limited relative rotation in either direction with respect to the member and arranged to move towards and away from the conductor and means movably mounted on the supporting member to limit the movement of the gripping means away from the conductor.

10. A conductor holder comprising a supporting member and means to secure the member to a hanger, clamping means to grip a conductor and having a limited relative rotation in either direction with respect to the member and arranged to move towards and away from the conductor and means movably mounted on the supporting member to limit the movement of the gripping means away from the conductor and means on the supporting member to engage the movably mounted means on the member to limit the movement of the movably mounted means.

11. A conductor holder comprising a supporting member provided with means to secure the member to a hanger, a pair of jaws rotatively mounted directly on the member for limited rotation in either direction and having means to grip a conductor, means on the member to engage the jaws to move them into engagement with the conductor and to limit the disengagement of the jaws with the conductor.

12. A conductor holder comprising a supporting member, a pair of independent jaws mounted on the member and movable relative to each other to engage or disengage a conductor and having a limited rotation relative to the member, means to limit the relative rotation, and means on the member to engage means on the jaws to maintain them mounted upon the member.

13. A conductor holder comprising a supporting member, a pair of independent jaws mounted on the member and movable relative to each other to engage or disengage a conductor and having a limited rotation relative to the member, means to limit the relative rotation and means movably mounted on the support to engage the jaws and limit their movement away from the conductor.

14. A conductor holder comprising a supporting member, means to secure the member to a hanger, clamping means rotatably mounted directly on the member and movable into clamping engagement with a conductor, means on the supporting member movable towards and away from the clamping means at will to force the clamping means into engagement with the conductor when moved towards the said clamping

means and to limit the opening of the said clamping means when moved away from the said clamping means and means to limit the rotation of the clamping means relative to the supporting member.

15. A conductor holder comprising a supporting member, means to secure the member to a hanger, clamping means rotatably mounted directly on the member and movable into clamping engagement with a conductor, means rotatably mounted on the supporting member to move the clamping means into engagement with the conductor when rotated in one direction and to move away

10 15 from the clamping member and permit the clamping means to release the conductor when rotated in the other direction, means to limit the movement of the rotatable means away from the clamping means and means 20 to limit the amount of rotation of the clamping means relative to the supporting member.

16. A conductor holder comprising a supporting member, means to secure the member to a hanger, clamping means rotatably mounted directly on the member and movable into clamping engagement with a conductor, means rotatably mounted on the supporting member to move the clamping means 30 into engagement with the conductor when rotated in one direction and to move away from the clamping member and permit the clamping means to release the conductor when rotated in the other direction.

35 17. A conductor holder comprising clamping means to grip a conductor, supporting means having a relative rotative movement with respect to the clamping means, means to limit the relative rotative movement, rotatable means to force the clamping means 40 into a holding engagement with the conductor and means to secure the holder to a hanger.

18. A conductor holder comprising clamping 45 members provided with inwardly projecting flanges, a member provided with an annular groove in which is rotatively positioned the projecting flanges on the clamping members, means to limit the amount of rotation, and rotatable means to engage the clamping members and force them into engagement with a conductor.

50 55 19. A conductor holder comprising clamping members provided with inwardly projecting flanges, a member provided with an annular groove in which is rotatively mount-

ed the projecting members, means associated with the above members coacting together to hold the clamping members in said annular groove, and rotatable means to engage the clamping members and force them into engagement with a conductor.

20. A conductor holder comprising a supporting member, a pair of independently acting clamping members fulcrumed on the support, an operating member movably mounted on the supporting member to engage and force the clamping members into clamping engagement with a conductor, retaining means on the clamping members coacting with retaining means on the supporting member to prevent dislodgement of the clamping members from the supporting members and means to limit the amount of movement of the operating member in a direction away from the clamping members.

21. A conductor holder comprising a supporting member having means to secure the holder to a hanger, a pair of clamping members mounted on the support, means integrally formed with the supporting member to engage means integrally formed with the clamping members to retain them on the support and means to move the clamping members into engagement with a conductor.

22. A conductor holder comprising a supporting member having means to secure the holder to a hanger, a pair of clamping members mounted on the support and having a sliding fulcrum and a substantially fixed fulcrum therewith, means on the supporting member to engage the clamping members to retain them on the support and means mounted on the support member to move the clamping members into engagement with a conductor.

23. A conductor holder comprising a supporting member and means to secure the holder to a hanger, a pair of clamping members to grip a conductor and mounted on the supporting member, means on the supporting member to engage the upper end of the clamping members to prevent their dislodgement from the supporting member when moved in a line at right angles to the normal vertical axis of the supporting member and means to move the clamping member into engagement with the conductor.

In testimony whereof I affix my signature.

HOMER P. CHANDLER.
